[57] **CLAIM**

The ornamental design for a livestock blow dryer, as shown and described.

DESCRIPTION

FIG. 1 is a right front perspective view of a livestock blow dryer according to the present invention;

FIG. 2 is a left rear perspective view of the livestock blow dryer of FIG. 1; and,

FIG. 3 is a front elevation view of the livestock blow dryer of FIG. 1.

The broken line showing of environment in FIGS. 1-3 is for illustrative purposes only and forms no part of the claimed design.
